UNITED STATES PATENT OFFICE.

JOHN Y. BASSELL, OF LEESBURG, VIRGINIA, ASSIGNOR TO REBECCA G. BASSELL, OF SAME PLACE.

WEATHER-STRIP.

SPECIFICATION forming part of Letters Patent No. 330,866, dated November 24, 1885.

Application filed September 3, 1885. Serial No. 176,114. (No model.)

To all whom it may concern:

Be it known that I, JOHN Y. BASSELL, of Leesburg, Loudoun county, Virginia, have invented certain new and useful Improvements 5 in Weather-Strips; and I do hereby declare the following to be a full, clear, and exact description of the same, reference being had to the accompanying drawings, forming part of this specification, and to the figures and letters of reference marked thereon.

My invention relates to that class of weather-strips in which a strip of rubber or other flexible material is combined with a strip of metal, which serves to hold the rubber, and constitutes 15 the part to which the attaching nails or screws are driven; and it consists in a certain novel adaptation of the said rubber to the metal, whereby economy in material is effected, and a more perfect and secure union of said parts 20 is accomplished.

I will first describe my invention at length, and will then point out in the clauses of the claim at the end of this specification what I deem to be its essentially novel feature.

25 Referring to the accompanying drawings, Figure 1 represents a perspective view of a section of weather-strip constructed in accordance with my invention. Fig. 2 represents a cross-sectional view of the same. Fig. 3 is a perspective view of a portion of the rubber strip as it appears before its application to the metal strip. Figs. 4 and 5 are views of modifications.

Similar letters of reference in the several figures indicate the same parts.

35 The letter A indicates the rubber portion of the device, and B the metal part thereof. By preference I take a strip of rubber of the desired dimensions and fold it partially back on itself, as shown in Fig. 3, so as to form a looped 40 or tubular portion, a, and a single ply or thickness, a', from the point a² to the point a³. I then unite the overlapped portion to the body of the strip by means of a line of stitching, s, applied as shown in Fig. 3; or, in lieu of the 45 stitching, I employ suitable rubber cement or other competent cement or glue for effecting the firm union of the parts. Having thus prepared the rubber, I connect to it, by means of suitable machinery adapted to the purpose, the 50 metal strip B in such manner as that one wing

or flange, b, of the metal will be overlapped and turned under the single thickness a' of the rubber, while the other flange, b', thereof will be made to embrace both plies a⁴ a⁵, as well as the third ply, a', of the rubber, as clearly shown in Fig. 2. The ply a⁴, it will be observed, terminates at the point a³, while the ply a⁵ continues beyond the said point, and is doubled back on itself so as to form the third ply, a'. This shortening of the ply a⁴ would not be practicable 55 were it not for the fact of its firm connection with the ply a⁵ by means of the stitching or otherwise, since without this connection it would pull out of the metal in handling before the application of the material to use. The 60 saving gained in thus shortening the rubber ply a⁴ amounts in the narrowest size of weather-stripping to at least one seventh or eighth of the whole quantity employed, while in wider sizes the proportion saved is still greater, owing 65 to the fact that in such sizes the relative width of the metal increases, and consequently the amount of rubber turned over within the metal is also increased. While I prefer to shorten the ply a⁴ and lap the ply a⁵ around it, so as to 70 form the third ply, a', the same saving of material may be effected by shortening the ply a⁵ and turning over the extended ply a⁴, as shown in Fig. 4. After the rubber and metal have 75 been connected as described, holes i, for the passage of the attaching-nails, are made by striking a punch (or a series of punches at a time) down through the metal strip, near its middle, as shown in Figs. 1 and 5. The forcing of the 80 punch through the metal causes an inwardly-projecting burr, j, to be produced, which extends through both of the upper superposed thicknesses or plies, a' and a⁴, of the rubber, as shown in Fig. 5, and serves as an efficient means for preliminarily holding the ply a⁴ within the 85 metal, and dispenses with the necessity of using stitches or cement for the purpose. Of course in the application of the strip the nails will pass down through the apertures thus formed, and will further firmly secure the rubber to the metal. For additional strength, however, I prefer to positively connect the 90 two plies of rubber together by stitching or otherwise before the metal is connected.

I am aware that weather-strips have been 95

made composed of a strip of rubber doubled, and both the ends clamped by a metal plate, as shown in Patent No. 92,613, granted C. A. Judd, July 13, 1869; but such a construction is inferior to mine, because not only is the metal strip with its double fold of rubber inside too bulky, but an unnecessarily large amount of the rubber or fabric is used, which is wasted, performing no function whatever.

10 Having thus described my invention, what I claim as new is—

15 1. In a weather-strip such as described, the combination of the flexible strip formed into a loop, as shown, by being overlapped on itself, and having a single thickness or ply, a' , left projecting beyond the top, with the metal strip having one wing turned in to embrace the extremity of the single ply or thickness a' , and

the other wing turned in to embrace all three plies, a^4 , a^5 , and a' , whereby a saving of flexible 20 strip is effected, substantially as described.

2. In a weather-strip such as described, the combination of the flexible strip formed into a loop, as shown, and having the plies constituting the loop sewed or otherwise positively secured together, with the metal strip having one wing turned in to embrace the extremity of the single ply or thickness a' , and the other wing turned in to embrace and hold all three plies, a^4 , a^5 , and a' , substantially as and for the 25 purpose set forth.

JOHN Y. BASSELL.
